United States Patent Office.

NICHOLAS BRAYER, OF ROCHESTER, NEW YORK, ASSIGNOR TO "EQUITABLE CO-OPERATIVE FOUNDRY COMPANY," OF SAME PLACE.

Design No. 4,588, dated January 24, 1871.

DESIGN FOR A HEATING-STOVE.

The Schedule referred to in these Letters Patent and making part of the same.

I, NICHOLAS BRAYER, of Rochester, in the county of Monroe and State of New York, have invented a new and original "Design for a Stove," of which the following is a specification.

My invention relates to a stove of oval form, having a fuel-door at the side and draught-register in front.

The top-plate and cover are each ornamented with a row of branching scrolls in relief, alternating with double cusps or spires, the latter broken at the center by hemispherical bosses, as shown in the accompanying photograph.

Between the branches of each scroll there is located a double cusp, formed by a row of hemispherical bosses decreasing in size from the center of the cusp each way.

The bottom-plate of the stove has also a row of scrolls and cusps arranged as above described.

Upon the face of the fuel-door are the words "New Live Oak," followed by the abbreviation "No.," and the number denoting the respective size of the stove.

The sheet-iron jacket may be crimped or corrugated, and ornamented with medallions or embossed figures, as is usual in this class of stoves.

What I claim is—

The design for a stove, substantially as herein set forth.

N. BRAYER.
